R. G. WILSON.

BRACKET FOR CONSTRUCTING CONCRETE WALLS.
APPLICATION FILED APR. 1, 1910. RENEWED MAY 16, 1913.

1,132,059.

Patented Mar. 16, 1915.

UNITED STATES PATENT OFFICE.

ROBERT G. WILSON, OF BROOKLYN, NEW YORK, ASSIGNOR TO MEAD-SUYDAM COMPANY,
OF EAST ORANGE, NEW JERSEY, A CORPORATION.

BRACKET FOR CONSTRUCTING CONCRETE WALLS.

1,132,059.

Specification of Letters Patent. Patented Mar. 16, 1915.

Application filed April 1, 1910, Serial No. 552,757. Renewed May 15, 1913. Serial No. 767,901.

To all whom it may concern:

Be it known that I, ROBERT G. WILSON, a subject of the King of Great Britain, and a resident of Brooklyn, in the county of Kings 5 and State of New York, have invented certain new and useful Improvements in Brackets for Use in Constructing Concrete Walls, of which the following is a specification.

My invention relates to devices or apparatus for use in concrete construction work and more particularly relates to means for retaining and positioning the side plates or members of a mold into the space between which the concrete is introduced to form a 15 wall or similar part.

My invention is particularly useful in constructing concrete green-house benches of the monolithic type wherein it is desired to provide the bench with side walls rising vertically from the bed or platform of the bench. In such cases if it is desired to have straight walls of even thickness and smooth finish, the concrete must be molded between long side plates forming the sides of the 25 mold and means provided for positively retaining or preventing these side plates from spreading or getting out of proper position. It is only possible to mount or support the means for retaining or holding the side plates on the outside of the bench or on but one side of the mold but it is essential that means be provided for both plates for holding them in their position or at least for preventing them from separating beyond a 30 predetermined amount. My invention contemplates the use of a bracket or device for this purpose which is entirely separate from the side plates and which is capable of being mounted on a fixed support on but one side 35 of the mold and adapted to engage both side plates thereof.

One of the objects of my invention is to provide means whereby the opposite side plates of a mold may be positively retained 45 in place and a wall of uniform thickness attained in such cases where it is possible to only mount or support the retaining means on one side of the mold or structure to be formed between the said side plates.

Another object of my invention is to provide simple and positively acting means whereby the same bracket or retaining means may be used for different thicknesses of wall it may be desired to form in the mold.

By my invention a number of the brackets

are placed along the side of the bench on which it is desired to form the side wall and the arms of the bracket set for the desired thickness of wall. The side plates of the mold are placed between the arms of the 60 brackets and the cement filled in between the plates until the plates are forced out as far as they will go against the arms of the brackets which limit the thickness of the wall. The brackets are so formed that the 65 usual spreader for forcing the cement down solid in the mold and the finishing tool for giving a smooth or special shaped top to the wall may be employed without removing the brackets.

It will be understood that my invention is not limited to use in constructing green-house benches, but it might be employed for various other uses without departing from the spirit thereof.

The invention consists in the novel devices, combination of parts and details of construction hereinafter more particularly described and then specified in the claim.

In the accompanying drawings, Figure 1 80 is a general transverse section and partial elevation of a monolithic green-house bench during the course of construction and having my invention applied thereto. Fig. 2 is a general side elevation of the same. Fig. 3 85 is a detached elevation of a bracket constructed in accordance with my invention. Fig. 4 is an edge view of the same. Fig. 5 is a plan view of the bracket.

In the drawings I show my invention as 90 applied for use in constructing a green-house bench of the general type shown and described in prior patent to John Wilson No. 889,349, dated June 2nd, 1908, as it is for this use that my invention in its preferred form is most particularly useful, although it will be understood that the invention is not in any way limited to use in this connection.

The bed or top of the bench 1 is formed 100 in any desired way and is provided with supports 2 as is usual.

3 and 4 indicate parallel plates rising vertically from the bed or top 1 at either side thereof and forming the side members of a 105 mold between which the sides or walls 5 of the bench are formed.

At intervals throughout the length of the bench, string-pieces 6, arranged in pairs are suitably supported below the bed 1 and in 110

a direction transverse to that in which the walls 5 are to be formed, each string-piece of any pair being spaced a suitable distance from its companion piece and the ends thereof 5 of projecting for a greater or less distance beyond the sides of the bed 1. The string-pieces 6 are preferably placed one either side of the bench supports or legs 2 and rest on ledges 15 formed on the sides of said supports. Bolts 16 passing transversely through the string-pieces clamp the same to the supports in an obvious manner.

The inner plate or member 3 of the mold is preferably provided with a flange which 15 rests upon the top of the bed 1, while the outer plate 4 which is somewhat longer preferably rests upon the string-pieces 6, the upper edge of each plate being preferably provided with a flange projecting laterally in 20 opposite directions.

7 indicates posts suitably supported at intervals along the wall or side to be formed and in the present embodiment are supported in the projecting ends of the string-pieces 6. The posts might be secured in any desired way to the string-pieces but are preferably positively held thereto by means of a suitable bolt 8 passing through the base flange 9 of the post 7 and through a plate 10 25 adapted to engage each string-piece of a pair and span the space between them. The post is clamped to the string-pieces by tightening up on a suitable wing-nut or other means whereby the base flange 9 of the post 30 and the plate 10 are squeezed up on either side of the string-pieces. By loosening the wing-nut the position of the post 7 may be 35 adjusted or varied as desired.

The upper part of the post 7 is preferably 40 provided with a laterally projecting arm provided with guides 11 within which a tongue 12 of a depending arm 13 works. The lower part of the post 7 is so formed that the outer plate 4 will rest against it, a 45 suitable ledge being preferably provided as a seat for the upper flange of the plate. The depending arm 13 engages the inner plate or side member 3 of the mold at its lower end and forms a stop or abutment 50 which limits the outward movement of the plate and supports it against lateral displacement, a suitable ledge being provided

on this arm for the flange on the upper edge of the plate 3. The arm 13 is secured to the post 7 by a pin and slot connection as shown 55 whereby the distance between the arms may be varied and thereby walls of greater or less thickness molded between them.

It will be noted that the bracket takes a general inverted U-shape and the concrete or 60 other material with which it is desired to form the wall is inserted between the side plates 3, 4 and forced down until the space between them has been solidly filled, there being sufficient space between the upper part of the 65 wall and the bracket for inserting the usual spreader for this purpose. After the mold has been filled up, the finishing tool is run along on top of the upper flanges of the plates 3, 4 and under the loop of the bracket 70 and the wall finished off, after which the brackets and other parts are removed.

17 indicates a groove formed in the inner or plate-engaging side of the post 7 and arm 13 below the ledges upon which the upper 75 flanges of the side plates 3 and 4 rest. These grooves form a depository for the upper flanges of side plates of less height than those shown and which are preferably used when constructing lower walls or sides. 80

What I claim as my invention is:

In a device of the character described, the combination of a post provided with a flange at its base forming an adjustable support and adapted to form a stop for a side member of a mold, an arm projecting laterally from the upper part of said post and provided with longitudinal guides and a depending arm forming a stop for the opposite side member of the mold and provided with 85 a lateral arm having a slot whereby said arm is adjustably secured to said post in said guides, the upper part of the post and the depending arm being offset to provide an increased space between them above the 90 parts forming the stops for the mold. 95

Signed at New York in the county of New York and State of New York this 8th day of March A. D. 1910.

ROBERT G. WILSON.
